UNITED STATES PATENT OFFICE.

EMIL GATHMANN, OF BALTIMORE, MARYLAND, ASSIGNOR TO CRUCIBLE STEEL COMPANY OF AMERICA, A CORPORATION OF NEW JERSEY.

PROJECTILE.

1,074,111.

Specification of Letters Patent.

Patented Sept. 30, 1913.

Application filed January 9, 1913. Serial No. 741,065.

To all whom it may concern:

Be it known that I, EMIL GATHMANN, residing at Baltimore city, State of Maryland, a citizen of the United States, have invented or discovered a certain new and useful Improvement in Projectiles, of which improvement the following is a specification.

It is the object of the invention to provide improved means for securing an impact or other cap to the point or forward portion of a projectile, which may be easily and economically applied, and will firmly lock the cap against any rotary movement. The invention also has the advantage that its use involves a minimum sacrifice of metal from the point of the projectile itself.

In the accompanying drawings Figure 1 is a view in longitudinal section of the forward portion of a projectile having a cap secured thereto in accordance with this invention in its preferred form; Fig. 2 is a view in cross-section upon the line II-II of Fig. 1.

The cap 1 has the usual rear cavity 2 adapted to fit upon the point 3 of the projectile. The approved practice heretofore has been to form a continuous peripheral groove in the surface of the point of the projectile, and to either force the metal of the cap into said groove, or to form a coöperating groove in the inner surface of the cap-cavity and to secure the cap in place by means of rods or keys inserted in the coöperating grooves. In the present invention, instead of a continuous peripheral groove being formed in the surface of the projectile-point, a plurality of fractional grooves 4 are formed in said surface, lying in a plane or planes at an angle to the axis of the projectile, and preferably perpendicular thereto. These grooves are preferably formed tangential to the surface as shown in the drawings, that is to say, having their axes lying in lines truly tangential to the surface, and their bases lying in straight lines forming chords of the peripheral circumference of the projectile-point.

Coöperating grooves 5 are formed in the inner surface of the cap-cavity, and passages 6, bored through the wall of the cap, communicate with said coöperating grooves, preferably at both ends thereof. Rods or keys 7 are then passed through said passages and said fractional coöperating grooves, and serve to firmly bind the cap to the projectile-point and to lock it against any rotation thereon. The outer edges of the passages 6 may be made slightly flaring and the ends of the keys be swaged down upon such flaring edges, as indicated at 8, in order to lock the keys against any longitudinal movement.

It will be obvious to those skilled in the art that the shape and form of the coöperating grooves and their relative arrangement may be varied without departure from the invention as defined in the appended claims.

I claim as my invention:

1. The combination of a projectile provided on its outer surface with a plurality of fractional grooves each lying in a plane at an angle to the axis of the projectile, a cap having a cavity adapted to fit upon the projectile, coöperating fractional grooves in the face of said cavity, passages through the cap communicating with said coöperating grooves, and keys inclosed in said passages and grooves.

2. The combination of a projectile provided on its outer surface with a plurality of tangential grooves each lying in a plane at an angle to the axis of the projectile, a cap having a cavity adapted to fit upon the projectile, coöperating grooves in the face of said cavity, passages through the cap communicating with said coöperating grooves, and keys inclosed in said passages and grooves.

3. The combination of a projectile provided on its outer surface with a plurality of fractional grooves each lying in a plane at an angle to the axis of the projectile, a cap having a cavity adapted to fit upon the projectile and coöperating grooves formed

in the face of said cavity, and means for securing the cap to the projectile engaging said coöperating grooves.

4. A cap for projectiles having a cavity adapted to fit upon the projectile, a plurality of fractional grooves formed in the face of said cavity, each groove lying in a plane at an angle to the axis of the cap, and pas-

10
sages through the cap communicating with said grooves.

In testimony whereof I have hereunto set my hand.

EMIL GATHMANN.
